LIONEL M. WOOLSON, OF DETROIT, MICHIGAN, ASSIGNEE TO PACKARD MOTOR CAR COMPANY, OF DETROIT, MICHIGAN, A CORPORATION OF MICHIGAN

INTERNAL COMBUSTION ENGINE

Application filed October 14, 1929. Serial No. 399,458.

This invention relates to internal combustion engines and more particularly to compression ratio changing mechanism.

An object of my invention is to associate compression ratio regulating mechanism with an internal combustion engine so that it can be rapidly varied through manual manipulation.

Another object of my invention is to provide a radial type of internal combustion engine with a manually adjustable compression ratio regulating mechanism which is contained wholly within the crank case.

A still further object of my invention is to provide an engine compression ratio adjusting mechanism which is carried by and anchored adjacent a counterweight of the crank shaft.

Another object of the invention is to provide a novel form of mechanism for regulating and fixing the relation of an eccentric upon a crank pin so that the entire compression ratio mechanism is compactly associated with the crank shaft in a manner such that it can be easily adjusted.

These and other objects of the invention will appear from the following description taken in connection with the drawings, which form a part of this specification, and in which:

In the accompanying drawings Fig. 1 is an elevational view of the fore part of an airplane partially broken away to show my improved form of compression ratio mechanism associated with the crank shaft of an engine;

Fig. 2 is a rear elevation of the engine shown in Fig. 1 having the rear case and a portion of one cylinder broken away and showing the association of the compression ratio regulating mechanism associated with the crank shaft;

Fig. 3 is a fragmentary sectional view taken on line 3—3 of Fig. 2;

And Fig. 4 is a sectional view of the compression ratio adjusting mechanism taken on line 4—4 of Fig. 2.

Referring now to the drawings by characters of reference, 10 represents generally the forward end of an airplane which in-

cludes a multi-cylinder radial type of engine. A crank case 11 extends forwardly of the fuselage of the airplane and is provided with a fixed diaphragm wall 12 and a removable diaphragm wall 13, such walls 12 and 13 providing a compartment into which the connecting rods extend and are associated with the crank shaft 14 which extends axially through the crank case. The crank shaft is of the single throw type and is supported in bearings, one of which is shown at 15 associated with the diaphragm 13. The crank shaft projects beyond the front end of the crank case and has fixed thereto a propeller 16 which is retained thereupon by a suitable thrust member and locking means.

The cylinders 17 are arranged radially of the crank case being preferably nine in number and equally spaced, such cylinders having portions 18 which extend through openings in the wall of the annular crank case. The cylinders also are provided with flanges 19 which bear against the outer surface of the crank case and are secured in such relation by a pair of circular bands 20 which are compressed. Such bands also serve the purpose of absorbing explosion loads from the cylinders and transferring the same annularly around the crank case, such method of transferring explosive loads in the cylinders to the crank case permitting the crank case to be formed of relatively thin walls which will have sufficient strength to withstand the compression pressures and explosions which occur in a Diesel type of engine. The crank shaft 14 is preferably formed in two sections the forward end of which includes an arm 21 and a crank pin 22 and the other end of which includes an arm 23 which is formed so that it can be assembled endwise upon the pin 22 and secured in position by the bolt 24, such type of crank shaft being well known in the art.

With a crank shaft and engine of the character described I purpose to associate compression ratio regulating mechanism which can be manually adjusted to determine the compression ratio within the cylinders. To this end I provide an eccentric sleeve 25 which is assembled by endwise movement

upon the crank pin 22 when the arm 23 is removed, such eccentric sleeve being retained upon the crank pin by securing the arm 23 in its operative position. Upon the eccentric sleeve 25 I mount the master rod 26 which encircles the eccentric and the rod portion of which extends into the uppermost cylinder. Rods 27 extend into the other cylinders of the engine and are pivotally mounted 10 in a circular relation to the hub of the master rod by pins 28 which extend through the master rod hub and one end of the rods 27.

The position of the eccentric sleeve 25 relative to the crank pin 22 will determine the compression ratio within the cylinders because when fixed in different annular positions with respect to the crank pin, the length of the movement of the rods 27 will vary and in this manner the compression ratio in 15 the cylinders is determined. In order to regulate and fix the position of the eccentric sleeve with respect to the pin 22 I provide mechanism, wholly within the compartment between the walls 12 and 13, which can be 20 manipulated manually. To this end, the eccentric sleeve is provided with an extension 29 to which an eye-bolt 30 is pivotally secured by the pin 31, such pin being secured 25 against axial displacement by a cotter pin 32. A bracket 33 is secured to the counterweight 33', on the removable arm 23 by rivets 32', such bracket extending beyond one side 30 of the counterweight and having a circular bore 34 formed in the projecting end thereof 35 for the reception of a cylindrical bearing 35. The projecting end of the bracket is also provided with an aperture 36 which extends transversely of the circular bore and is arranged to permit the eye-bolt to extend there 40 through. The bearing 35 is provided with a threaded aperture 37 which is arranged in alignment with the aperture 36 in the bracket so that the eye-bolt can also pass through. An internally and externally threaded sleeve 45 45 is screwed into the threaded aperture of the bearing member and is also screwed upon the threaded end of the eye-bolt, such sleeve having the end 39 formed to receive a wrench or similar tool for rotating the same. The 50 internal and external threads of the sleeve 38 extend in opposite directions and with such right and left hand threads rotation of the sleeve 38 will thus transmit a multiplied movement to the eye-bolt 30. As the eye-bolt 55 extends through the bearing 35 it cannot be displaced axially of the bore 34 and to secure the sleeve 38 in desired adjusted position with respect to the eye-bolt, I provide a jam bolt 40 which extends through an aperture 60 in the bearing member 35 and can be adjusted to engage against the threaded periphery of the sleeve. The jam bolt is formed of softer material than the sleeve so that it will not mutilate the threads.

65 It will be seen that the bearing member

35 can be rotated within the bore 34 so that the variable angular position which the eye-bolt 30 must assume will be permitted, in other words the adjustment of the eye-bolt will change its angular relation with respect to the counterweight and such change of position will be permitted through the similar movement transmitted to the bearing member 35. It will also be seen that rotation of the sleeve 38 will cause the extension 29 and the eccentric sleeve, which is integral therewith, to change its position rotatably with respect to the crank pin 22 and thereby vary the stroke of the piston rods because of the resulting movement of the master rod 29 hub in a different plane. Movement of the extension 29 downwardly from the position shown in Fig. 2 will cause the eccentric to be moved to a position such that the compression ratio is increased, whereas movement of the extension 29 upwardly will cause a decrease in the compression ratio.

As before stated the engine illustrated is of the Diesel type and operates upon a four cycle stroke. Pistons 41 are arranged to 90 reciprocate within the cylinders and motion is transmitted therefrom to the crank shaft by the connecting rods. A passage extends through each of the cylinder heads 42 and air is drawn therethrough upon the suction 95 stroke of the pistons, whereas the exhaust is expelled therethrough upon the scavenging stroke of the pistons. During the compression stroke of the pistons, liquid fuel is sprayed into the compressed air by means of 100 fuel injecting devices 43 which are associated one with each cylinder. A suitable manifold 44 is associated with the fuel injecting devices for supplying them with liquid fuel, such conduit communicating with a source 105 of fuel supply. My co-pending application, Serial No. 358,899, filed April 29, 1929, illustrates and describes in detail an engine of the character generally set forth herein, and reference may be had thereto for a more complete 110 understanding of the operation of a Diesel engine with which this invention can be associated. However, the invention can be applied to any radial form of internal combustion engine, whether the combustion 115 is produced by compression or by some auxiliary means.

It will be seen that the compression ratio regulating mechanism herein described and illustrated is light in weight, compact and quickly adjustable, and that it is contained entirely within the compartment of the crank case which houses the connecting rods and the crank of the crank shaft.

While a specific embodiment of the invention has been herein described, which is deemed to be new and advantageous and may be specifically claimed, it is not to be understood that the invention is limited to the exact details of the construction, as it will be ap- 125

parent that changes may be made therein without departing from the spirit or scope of the invention.

What I claim is:

1. In a radial type explosion engine, the combination with the crank shaft and master connecting rod, of a compression ratio changing device comprising an eccentric sleeve intermediate the crank shaft and the master rod bearing, and means carried entirely by the crank shaft for regulating the position of the eccentric sleeve upon and fixing it relative to the crank shaft. 70
2. In a radial type explosion engine, the combination with a counterweighted crank shaft and master connecting rod, of a compression ratio changing device comprising an eccentric sleeve intermediate the crank shaft and the master rod bearing, and means attached to the crank shaft counterweight for 75 fixing the sleeve upon the crank shaft. 80
3. In a radial type explosion engine, the combination with the crank shaft and master connecting rod, of a compression ratio changing device comprising an eccentric sleeve intermediate the crank shaft pin and the connecting rod bearing, and means pivotally connected to the sleeve and attached to the crank shaft for adjusting and fixing the 85 sleeve on the crank pin. 90
4. In a radial type explosion engine, the combination with a counterweighted crank shaft and master connecting rod, of a compression ratio changing device comprising an eccentric sleeve intermediate the crank shaft pin and the connecting rod hub, an eye-bolt pivoted to the sleeve, and adjustable means carried by a counterweight of the crank shaft for anchoring the eye-bolt in a desired position to control the position of the sleeve. 100
5. In a radial type explosion engine, the combination of a counterweighted crank shaft and master connecting rod, of a compression ratio changing device comprising an eccentric sleeve intermediate the crank pin and the connecting rod bearing, said sleeve having a flange, and means connected with the sleeve flange and the counterweight fixing the sleeve in desired relation with the crank pin. 105
6. In a radial type explosion engine, the combination of a counterweighted crank shaft and master connecting rod, of a compression ratio changing device comprising a flanged eccentric sleeve intermediate the crank pin and the connecting rod bearing, and adjustable means connected with the sleeve flange and the counterweight fixing the sleeve in desired relation with the crank pin, said means including motion multiplying mechanism. 110
7. In a radial type explosion engine, the combination of a counterweighted crank shaft and master connecting rod, of a com- 115
- 120
- 125

pression ratio changing device closely associated with the crank throw comprising an eccentric sleeve intermediate the crank pin and the rod bearing, a movable bearing carried by a counterweight of the crank shaft, a rigid connection extending between the sleeve and the bearing, and adjustable means securing the connection with the bearing.

8. In a radial type explosion engine, the combination of a counterweighted crank shaft and master connecting rod, of a compression ratio changing device comprising an eccentric sleeve intermediate the crank pin and the rod hub, a bracket fixed to a shaft counterweight, and adjustable means pivoted to the sleeve and anchored to the bracket for positioning the sleeve relative to the crank pin. 75

9. In a radial type explosion engine, the combination with the crank shaft and master connecting rod, of a compression ratio changing device comprising a flanged eccentric sleeve intermediate the crank pin and the rod bearing, and a rigid connecting member pivoted to the sleeve flange and anchored to the crank shaft, said member being adjustable to rotatably vary the relation of the sleeve on the crank pin. 85

In testimony whereof I affix my signature.

LIONEL M. WOOLSON. 95
